UNITED STATES PATENT OFFICE.

PETER S. SORENSEN, OF NORTH MILWAUKEE, WISCONSIN, ASSIGNOR OF ONE-THIRD TO
FRANK R. LUECK AND ONE-THIRD TO WILLIAM F. FICHLFELD, BOTH OF MILWAU-
KEE, WISCONSIN.

COMBINATION WALL-BED, WARDROBE, AND DRESSER.

1,242,382.

Specification of Letters Patent.

Patented Oct. 9, 1917.

Application filed February 24, 1914. Serial No. 820,519.

To all whom it may concern:

Be it known that I, PETER S. SORENSEN, a citizen of the United States, and a resident of the city of North Milwaukee, in 5 the county of Milwaukee and State of Wisconsin, have invented certain new and useful Improvements in Combination Wall-Beds, Wardrobes, and Dressers; and I do hereby declare that the following is a full, 10 clear, and exact description of the same, reference being had to the accompanying drawings, and to the numerals of reference marked thereon, which form a part of this specification.

15 A number of various types of folding beds have been placed upon the market so constructed that when the bed is not in use as a bed, it is readily convertible into use as another article of furniture.

20 This invention, however, relates to a bed construction adapted to be built in the wall of a room and when extended for use, affording access to a clothes closet and a dresser concealed in the wall and brought 25 into operative position by extension of the bed.

It is an object of this invention to provide a folding bed structure built into the wall of a room serving to conceal, when in 30 folded position, a dresser and wardrobe, and when extended permitting parts of the wardrobe and the dresser to be swung outwardly in a convenient position.

It is also an object of this invention to 35 construct a bed foldable into a compartment in the wall of a room and operatively connected with a wardrobe and dresser normally concealed within the compartment when the bed is in folded position, in a 40 manner such that the wardrobe and dresser serve as a counterbalance for the bed to enable the same to be operated into its various positions with little effort.

It is also an object of this invention to 45 provide a rigid bed structure foldable into a recess in the wall of a room, and so constructed that the bed frame and the bedding thereon are maintained in the same relative relation irrespective of movements of 50 the bed frame.

It is also an object of this invention to construct a rigid non-collapsible bed frame

which is mounted to move as a whole into a recess within a wall of a room and, when extended, serving to elevate a wardrobe 55 cabinet into convenient position in said recess permitting a dresser to be swung outwardly therefrom alongside the bed at a convenient height above the floor.

It is also an object of this invention to 60 provide a combination bed, wardrobe and dresser construction in which a dresser and wardrobe are contained within a suitable cabinet hung on links within a recess in a wall, and serving as a counter-weight for 65 a bed adapted to be swung downwardly from the wall into position for use, such movement serving to elevate and project the cabinet forwardly, permitting the dresser to be swung outwardly alongside the 70 bed at a convenient height from the floor also giving access to the interior of the cabinet as a wardrobe.

It is furthermore an object of this invention to provide a combination bed, wardrobe and dresser construction wherein a substantially rigid bed frame is contained 75 in a substantially vertical position within the recess in a wall when in position out of use, and is swingingly supported upon links 80 within said recess and also braced at its middle and outer ends by bars pivoted in the recess permitting the bed frame to be swung outwardly and lowered into horizontal position; and with a wardrobe and 85 dresser supported in said recess upon the links supporting the bed frame, permitting said wardrobe and dresser to be projected forwardly and upwardly when the bed is lowered for ready access to said dresser and 90 wardrobe.

It is finally an object of this invention to provide a combination bed, wardrobe and dresser construction normally concealed within a recess in the wall of a room with 95 the understructure of the bed frame acting to close the recess.

The invention (in a preferred form), is illustrated in the drawings and hereinafter more fully described.

In the drawings:

Figure 1 is a front face view of a device with the bed frame lowered into position for use, the dresser swung outwardly

to one side, and the door of the wardrobe opened to the other side.

Fig. 2 is a similar front face view of a device in closed position.

5 Fig. 3 is a section on line 3—3 of Fig. 2, with the extended position of the parts shown in dotted lines.

Fig. 4 is a rear view taken on line 4—4 of Fig. 3, with the parts in extended position.

10 Fig. 5 is a fragmentary section taken on line 5—5 of Fig. 4, with the outer extremity of the bed frame broken away.

Fig. 6 is a similar view of the outer extremity of the bed frame broken away in 15 Fig. 5.

Fig. 7 is a fragmentary section on line 7—7 of Fig. 5, taken at one side of the bed frame, and showing in dotted lines the head board of the bed elevated in position for use.

20 Fig. 8 is a fragmentary section taken on line 8—8 of Fig. 4, illustrating a link connection between the cabinet and the frame.

Fig. 9 is a fragmentary section taken on line 9—9 of Fig. 5.

25 As shown in the drawings:

The side wall of a room is indicated as a whole by the reference numeral 1, and the floor by the numeral 2. A rectangular frame comprising a base 3, side members 4, and a 30 top 5, is built into a recess forming the interior walls thereof, in the wall of the room, and mounted on said frame members is the combination bed, wardrobe and dresser embodying the principles of my invention.

35 Liner plates 6, are secured flat against each of the side frame members 4, extending longitudinally thereof from the top to the bottom of the frame, but, of course, it is obvious that either one or both thereof may 40 be replaced as desired with two or more plates secured on the side wall members 4, at the proper points for attachment of the respective members of the device.

45 The bed frame consists of angle irons 7, forming the side members thereof, rigidly joined together at their outer ends by a transverse angle iron 8, and intermediate their ends by means of another angle member 9, the distance between said transverse 50 angle iron members 8 and 9, being equal to that of the ordinary length of bed. Said side bed frame members 7, are rigidly spaced apart at their inner ends by means of a rod 10, and brazed or welded to said inner ends 55 of each of said side frame members 7, and extending substantially at right angles thereto in a vertical plane, are bracket plates 11. Links 12, each pivoted upon a stud 13, are secured on the respective liner plates 6, 60 on each side of the recess in the wall, and a horizontal circular bar 14, extends between said links 12, rigidly connecting the same together. Said bar also extends through apertures in the respective bracket 65 plates 11, on the bed frame, thus supporting

the inner ends of the bed frame pivotally upon said bar 14.

Stop members 15, are secured on the surface of the respective liner plates 6, to be contacted by the links 12, on the bed frame 70 when the bed is extended or lowered, thus limiting the movement of said links and bed. Long and short brace bars of angle cross-section are pivotally connected in pairs on each side of the bed frame to aid 75 in supporting the same when in lowered position.

The long brace bars 16, are pivotally connected to the outer ends of the side frame members 7, by means of a pintle bar or rod 80 17, rigidly secured to the outer ends of said bars 16, engaging through slots in said members 7, and the short brace bars 19, are pivoted substantially at the middle of the side frame bed members 7, with common 85 pivots 20, one each connecting the pair of long and short brace bars at their inner ends near the bottom on the liner plates 6. The inner end of said bed frame, when in a lowered position is pivotally supported upon 90 said bar 14, and to prevent the bed frame from swinging downwardly into contact with the floor, said brace bars 16 and 19, are used as compression members to hold the bed frame in extended position. 95

Head and foot board members 18 and 18^a, respectively, are mounted on the bed frame, the former adjustable to permit folding of the same toward the bed frame, and the latter rigidly secured upon the end member 7. 100

A substantially rectangular cabinet 21, is mounted in the recess in the wall and, on its bottom near each side, is provided with forked bearing members 22, which engage over the pivot rod 14, connecting said links 105 12, thus serving to support the cabinet thereon. On each of its sides near its upper end, said cabinet is pivotally connected in the recess by cranks 23, which are pivoted upon studs 24, serving to guide and maintain the upper end of the cabinet in proper position as the same is raised and lowered with the rotational movement of the supporting links 12. Of course, weights may be contained in said cabinet to effect an accurate balancing of the bed frame structure, which is also hung upon the pivot bar 14, but in the present instance the weight of the cabinet itself is deemed sufficient for a ballast. 115

Doors 25 and 26, respectively, are hinged on the side wall of the cabinet 21, to close the front thereof and are adapted to swing into the open position shown in Fig. 1, to permit access to the interior of the cabinet. 125 Hooks 27, are provided on the inner surface of the door 26, and likewise may be conveniently furnished within the cabinet 21, although not shown, for wardrobe purposes. Rigidly connected to and supported 130

on said door 25, is a dresser 28, provided with a mirror 29, and drawers 30. When the door 25, is in the open position shown in Fig. 1, the dresser is at a convenient 5 height above the floor, and when the door is closed, of course the entire dresser is contained within the cabinet 21.

Hingedly mounted upon the base 3, of the recess frame, and projecting in front of the 10 rod 10, is a base board 31, which, when the bed is lowered for use, is thrust forwardly between the side frame members 7, by said bar, and lies flush with the front edge of the cabinet 21, affording a finished appearance 15 and concealing the mechanism. When the bed is in folded position, said base board 31, swings slightly rearwardly, as shown in Fig. 3, with its upper edge resting against the doors of the cabinet 21. A wall section 32, 20 provided with a mirror 33, is hingedly connected upon the base frame member 3, and, at its outer or upper end provided with slotted lugs pivotally connected upon the transverse rod member 17.

Accordingly, when the device is in closed 25 position, as shown in Fig. 2, the entire wall presents a finished appearance, said section 32, closing the recess with the mechanism contained therein, and adding a decorative 30 effect to the room. A ventilator 34, is provided in the top frame member 5, in order to permit a circulation of air through the recess.

The operation is as follows:

Referring to Fig. 5, it is clearly evident 35 that the cabinet 21, containing the wardrobe and dresser, is almost entirely supported upon the pivot bar 14, as is also the inner end of the bed frame. When the bed is in 40 extended position and the outer end of the bed frame is elevated a slight amount to raise the bed, the links 12, rotate inwardly until the pivot bar 14, passes a dead center position, thus shifting the weight of the cabinet 21, to the opposite side of the pivoted 45 studs 13, whereupon the weight of the cabinet 21, tends to cause said links 12, to move downwardly and inwardly, pulling the bracket plates 11, therewith and causing an 50 elevation of the bed frame. The cranks 23, at the upper end of the recess, connected to the cabinet 21, serve to guide the upper end of the cabinet and project the same forwardly when the cabinet is elevated by the 55 lowering of the bed.

The weight of the cabinet and mechanism should preferably be such as to slightly overbalance that of the bed frame structure, thus requiring the bed frame to be pulled down- 60 wardly in unfolding of the same, and of course, when the links 12, pass the dead center position, the weight of the cabinet then being disposed upon the same side of the pivots 13, as the bed frame, there is no 65 danger of the bed accidentally folding up.

However, when the device is to be folded up, the operator lifts the outer end of the bed frame until the cranks 12, pass dead center, whereupon the weight of the cabinet, with the very slight assistance of the operator, 70 serves to move the members of the device into closed position.

I am aware that various details of construction may be varied through a wide range without departing from the principles 75 of this invention, and I therefore do not purpose limiting the patent granted otherwise than necessitated by the prior art.

I claim as my invention:

1. In a device of the class described a wall 80 having a compartment therein, links pivotally mounted therein, a bed frame pivoted on said links and adapted when not in use to be swung within said compartment, and when in use to be swung outwardly therefrom into the room, brace bars pivotally connected on the bed frame and at their inner ends pivoted within said compartment, a wardrobe supported upon said links and adapted to counter-balance the weight of the 85 bed frame, and stops secured in said compartment to limit the movement of said links after the same have passed a dead center when the bed is lowered into position for use, permitting the weight of the wardrobe 90 to prevent accidental folding up of the bed frame.

2. In a device of the class described a bed 100 adapted to swing into a compartment in the wall of a room, brace bars mounted on pivots within the compartment and pivotally connected at their ends upon said bed to brace the same when in position for use, links within said compartment, the inner end of said bed pivotally supported thereon, a 105 cabinet member within the compartment also supported upon said links, and stops to limit the movement of said links.

3. In a device of the class described a bed 110 frame adapted to swing into a compartment in the wall of a room, brace bars mounted on a common pivot within the compartment and pivotally connected at their ends at different points upon said bed frame to brace the same when in position for use, links pivotally mounted within said compartment, the inner ends of said bed frame pivotally supported thereon, a cabinet member within the compartment supported upon said links, cranks pivotally connected to the upper end 115 of said cabinet and to the walls of the compartment, and stops secured within said compartment to limit the movement of said links.

4. The combination with a recessed wall, 125 of a swinging bed adapted to swing into the recessed wall, oblique supporting bars pivotally connected to said wall for supporting said bed when same is in open position for use, said bars acting as the sole supporting 130

means for said bed, and counterweight means for holding said bed in closed position.

5. In a device of the class described built into a wall having a ventilated recess, comprising a wall frame rigidly fitted into said recess, a folding bed, supporting means pivotally secured to said bed and said frame, a combination wardrobe and dresser ballast 10 means, and link supporting mechanisms piv-

otally connected to said ballast means and said frame.

In testimony whereof I have hereunto subscribed my name in the presence of two subscribing witnesses.

PETER S. SORENSEN.
